UNITED STATES PATENT OFFICE

132,661

DESIGN FOR A TOY PISTOL

Jacob E. Brubaker, Lancaster, Pa., assignor to The Hubley Manufacturing Company, Lancaster, Pa., a corporation of Pennsylvania

Application December 16, 1940, Serial No. 97,367

Term of patent 7 years

To all whom it may concern:

Be it known that I, Jacob E. Brubaker, a citizen of the United States, residing at Lancaster, in the county of Lancaster and State of Pennsylvania, have invented a new, original, and ornamental Design for a Toy Pistol, of which the following is a specification, reference being had to the accompanying drawing, forming part thereof.

Figure 1 is a perspective view of the toy pistol
showing my new design.

Figure 2 is a top plan view of the toy pistol

Figure 3 is a front elevation of the toy pistol
shown in Figure 1.

I claim:

The ornamental design for a toy pistol, substantially as shown.

JACOB E. BRUBAKER.
